United States Patent Office.

R. WILSON, OF REES CORNERS, MARYLAND.

Letters Patent No. 92,413, dated July 6, 1869.

IMPROVED REVOLVING DINING-TABLE.

The Schedule referred to in these Letters Patent and making part of the same.

To all whom it may concern:

Be it known that I, R. WILSON, of Rees Corners, in the county of Kent, and State of Maryland, have invented a new and useful Improvement in Revolving Dining-Table; and I do hereby declare that the following is a full, clear, and exact description thereof, which will enable others skilled in the art to make and use the same, reference being had to the accompanying drawing, forming part of this specification, in which—

Figure 1 is a top view of my improved table, part being broken away to show the construction.

Figure 2 is an end view of the same, partly in section, through the detachable fixed leaves.

Figure 3 is a detail sectional view of the same, taken through the line $x-x$, fig. 1.

Similar letters of reference indicate corresponding parts.

My invention has for its object to furnish an improved dining-table, which shall be so constructed and arranged that the plates and other dishes which the guests use in dining may stand upon a stationary part of the table, and the dishes from which the guests are served may stand upon the revolving part of the table, so that each guest may bring any desired dish within his reach; and

It consists in the construction and combination of the various parts of the table, as hereinafter more fully described.

A is the frame of the table, which is supported upon and attached to legs B, of suitable length.

C is the circular top of the table, to the centre of which is attached a spindle, or pivot D, which passes down through and revolves in a socket formed in or attached to the central cross-bar of the frame A, so that the said circular top may revolve freely.

To the upper ends of the legs B, or to convenient parts of the frame A, are pivoted friction-rollers E, upon which the top C rests, to diminish the friction, as the said top is revolved.

Notches or grooves may be formed in the under side of the top C, near its outer edge, to receive the fingers, for convenience in revolving it.

F are drawers, passing in through holes in the end-bars of the frame A, and having tongues formed upon their sides, which enter and fit into grooves formed to

receive them in the bars, between which the said drawers move in and out.

The drawers F may be provided with locks, the bolts of which shoot into sockets formed in the under side of the revolving top C, to hold the said top stationary when desired.

The drawers F should be provided with pins, or other stops, to prevent the said drawers from being drawn out too far.

G are the stationary detachable leaves, which surround the central revolving top C, and which are made in two parts, connected to each other, when in place upon the table, by dowel-pins, as shown in fig. 1.

In attaching the leaves G, the drawers F are drawn out and the leaves G adjusted about the revolving top C, in such a way that the joints of said leaves may be directly above the said drawers F, and the ends of both leaves be securely supported.

The middle parts of the leaves G may be supported by arms H, pivoted or hinged to the side-bars of the frame A, as shown in figs. 1 and 2.

In the case of small or cheap tables the drawers F may be replaced by sliding pivoted or hinged bars, which must be of such a width as to support the ends of both leaves.

When not required for use, the leaves G are detached and laid aside, and the drawers and arms closed, reducing the table to the form of an ordinary round centre-table. Two or more of these tables may be set together when desired; but in this case the adjacent leaves should be made narrow, so as to leave only a very narrow stationary part between the revolving tops of the adjacent tables.

Having thus described my invention,

What I claim as new, and desire to secure by Letters Patent, is—

The combination of the detachable stationary leaves G, circular central revolving top C, drawers F, or equivalent, and pivoted or hinged arms H, with each other and with the frame A, B, substantially as herein shown and described, and for the purpose set forth.

R. WILSON.
